United States Patent Office

Des. 207,901
Patented June 13, 1967

207,901

BATHING CAP

David Atkin, London, England, assignor to The Cannon
Rubber Manufacturers Limited, London, England
Filed Nov. 22, 1966, Ser. No. 4,772

Claims priority, application Great Britain Sept. 6, 1966

Term of patent 14 years

(Cl. D2—238)

FIG. I.

FIG.2

FIG. 1 is a front perspective view of a bathing hat showing my new design; and
FIG. 2 is a rear perspective view thereto.

The essential features of my design reside in the full line disclosure on the drawing.

I claim:

The ornamental design for a bathing cap, substantially as shown and described.
